Primary Examiner — Mitchell I. Siegel(74) *Attorney, Agent, or Firm* — William C. Schrot; AuerbachSchrot LLC(57) **CLAIM**

The ornamental design for a golf putting aid, as shown and described.

DESCRIPTION

FIG. 1 is a top rear perspective view of a golf putting aid according to the invention;

FIG. 2 is a top front perspective view of the golf putting aid of FIG. 1;

FIG. 3 is a front view of the golf putting aid of FIG. 1;

FIG. 4 is a rear view of the golf putting aid of FIG. 1;

FIG. 5 is a top view of the golf putting aid of FIG. 1;

FIG. 6 is a bottom view of the golf putting aid of FIG. 1;

FIG. 7 is a right side view of the golf putting aid of FIG. 1; and,

FIG. 8 is a left side view of the golf putting aid of FIG. 1. The portions shown in broken line are for illustrative purposes only and form no part of the claimed design.
